UNITED STATES PATENT OFFICE.

DAVID SCOTT ALLISON, OF SALT LAKE CITY, UTAH

AUTOMATIC-DUMPING MINING-CAR AND TIPPLE.

1,278,551.

Specification of Letters Patent. Patented Sept. 10, 1918.

Application filed March 9, 1918. Serial No. 221,450.

To all whom it may concern:

Be it known that I, DAVID SCOTT ALLISON, a citizen of the United States, residing at Salt Lake City, in the county of Salt Lake and State of Utah, have invented certain new and useful Improvements in Automatic-Dumping Mining-Cars and Tipplers; and I do hereby declare the following to be a full, clear, and exact description of the invention, such as will enable others skilled in the art to which it appertains to make and use the same.

The present invention relates to automatic dumping mining cars and tipplers, and has for its principal object to provide an apparatus of this character which will be entirely automatic in action, both to provide for dumping the loaded car at the proper destination over the bins and without the aid of workmen to again close the dumping doors of the cars and restore such doors to locked condition, in which they may be returned for subsequent loading.

Another object of the present invention lies in providing a car of improved construction as respects its strength and dumping facilities.

I also provide automatic dumping or tripping means for the dumping doors of the car which will operate on the door releasing mechanism carried by the car when such car is moved therewith in one direction, but which tripping means co-operates with further parts on the car to effect the removal of the tripping means from the path of the door controlling means when the car is reversed in direction.

In the accompanying drawings forming a part of this application, and in which similar reference symbols indicate corresponding parts in the several views:

Figure 1 is a fragmentary top plan view of an apparatus constructed in accordance with my present invention.

Fig. 2 is a longitudinal sectional view taken on the line 2—2 in Fig. 1.

Fig. 3 is a cross sectional view taken on the line 3—3 in Fig. 2.

Fig. 4 is an enlarged top plan view of the car.

Fig. 5 is a vertical central sectional view taken on the line 5—5 in Fig. 4; and

Fig. 6 is a transverse central view through the car.

Referring more particularly to the drawings, 1 designates a car traveling on the

tracks 2 elevated at the point indicated at 3 above the bins into which the material is to be deposited.

The car 1 is of any desired construction throughout, except that I prefer to form the same with a hollow substantially inverted V-shaped false bottom 3' made to extend transversely at substantially the center of the car, and affording the inclined surfaces 4 and 5 sloping downwardly toward the ends of the car 1, which by virtue of their shape act in the capacity of chutes for directing the material through the dumping doors 6 and 7. The construction and position of the false bottom 3' also aids materially in stiffening the car body.

The doors 6 and 7 as shown in the embodiment of my invention illustrated, are two in number, and when in the closed position, as they appear in Fig. 5, constitute together with the chutes 4 and 5 the bottom of the car. The forward door 7 is held in its normally closed position by one or more latches 8; two such latches being preferable, as indicated in dotted lines in Fig. 4, the same being connected together by a bar 9 and simultaneously projected and retracted into and out of locking position by movement imparted through an arm 10 from a lever 11 pivoted centrally of the car, as indicated at 12.

To the opposite side of the lever fulcrum 12 to that to which the arm 10 is attached, is coupled a second arm 13 adapted to project and retract a pair of latches 14 that slide in guideways 15 carried beneath the rear door 6, and the ends of which latches are adapted to be received in the lock strikes or sockets 16 carried by the car body adjacent the rear end. A bar 17 connects the two latches 14, and hinged joints 18 are made in such latch rods for the purpose of permitting the door 6 to swing down without interference, as shown in Fig. 2. Both doors 6 and 7 are hinged to the car body, as indicated at 19 and 20, respectively, so that they may swing down in the same direction when the latches are released and may dump the load in the bins 3.

This dumping of the load is accomplished automatically by extending the ends of the lever 11 outwardly beyond the sides of the car 1, as indicated in Figs. 1 and 4, where one of such projecting ends will lie in the path of a trip apparatus.

The trip apparatus is composed of long

lever 21 and short lever 22, mounted together on a shaft 23. Lever 21 is equipped with a counterweight 24, which is just heavy enough to keep the lever normally in a vertical position. Lever 22 is equipped with a counterweight 25, which is heavy enough to give sufficient resistance to open the car doors through the lever 11 on the car, and which, together with stop 26, maintains lever 22 normally in a vertical position.

To the left hand side of the car 1, shown in Figs. 1 and 2, and on the opposite side of the track to the trip apparatus just described, is placed a second trip apparatus 15 preferably composed of a long lever 30, associated with the short lever 29, the long lever being held upright by the weights 32 and weights 31 being employed to hold the short lever 29 in the vertical position shown.

20 The doors 6 and 7 carry rollers 35 and 36 disposed in the path of an inclined plane 37 faced with a metal wear plate 38, whereby such doors are moved from the open to the closed position, as indicated in Fig. 2.

25 A platform 39 is arranged between the track rails 2 adjacent the inclined plane 37, and is preferably supported yieldingly by the resilient springs 40. A wear plate 41 on this platform 39 has projecting and downwardly extending end pieces 42 and 43, the latter being in the nature of a bridge over which the rollers 35 and 36 may pass from the inclined plane to the platform.

30 When the rollers 35 and 36 are on the platform 39 the dumping doors 6 and 7 are held yieldingly in the closed position. The yielding action of the springs 40 serves to compensate for any wear upon the plate 41 and causes the platform to be urged upwardly to hold the doors tightly closed.

35 The operation of the invention is carried on in substantially the following manner:

40 One, or a train of such cars as shown at 1, after being loaded at a point to the right of the tracks 2 shown in Figs. 1 and 2, are moved to the left from the loading point along such tracks 2, and as each succeeding car passes over that portion of the track ele- 45 vated above the bins 3 its dumping doors 6 and 7 will be released and the load carried deposited. This dumping action is the re- 50 sult of the projecting end of the lever 11 striking the trip 21, which will cause such

55 lever to be shifted from the position shown in Fig. 4 to that shown in Fig. 1. As this shifting of the lever takes place the latches 8 and 14 will be withdrawn from the parts they engage, and the doors will fall by 60 gravity and discharge the load, which will be eased in its passage from the car by the presence of the chutes 4 and 5.

65 After the car passes the dumping point 3 and continues in its progress to the left in Fig. 2, the rollers 36 and 35 on the doors

7 and 6 will be caused to encounter and ride up upon the inclined plane 37, 38. Such doors are thereby returned to the closed position where they will be held closed after the rollers 36 and 35 pass to the platform 70 39. While the doors 6 and 7 are still held closed by the platform 39 the opposite end of the lever 11 will strike the trip 30 and will be restored to the original position shown in Fig. 4, operating at the same time 75 to project the latches 8 and 14 into engagement with their respective parts by which the doors are re-locked. The cars with their doors thus re-locked may pass on to the left until the last of the train has been dumped 80 and its doors returned to closed and locked position, whereupon the motion of the train may be reversed to bring the empty cars back to the original point for the succeeding 85 load.

As the cars return, the rollers 35 and 36 on the doors 6 and 7 will encounter the curved end piece 42, which will ease their passage over the platform 39 and cause the platform to be slightly depressed, this movement being absorbed by the springs 40.

When the car approaches from the right, lever 11 comes in contact with lever 21, which is made in two pieces riveted together so that, when pushed toward the left, it 95 presses against lever 22, and so acquires the resistance furnished by the counterweight 25, which is sufficient to move lever 11 and so withdraw the latches and allow the doors to open. When the car approaches the closing trip from the same direction, the same arrangement operates to close the latches.

When the car is moved along the track toward the right, the projection 34, rigidly attached to the car frame, comes in contact 100 with the lever 30, which, when moved toward the right, is free from any connection with the lever 29, and is restrained only by its own counterweight 22, which is only 105 heavy enough to restore lever 30 to a vertical position again after the car has passed. When the car approaches the first, or opening trip from the left, the lever 11 comes directly in contact with the lever 21 which, restrained only by its own counterweight 24, 110 is readily depressed so as to allow of the car passing.

115 From the foregoing description it will be appreciated that the load is dumped, the dumping doors subsequently closed and relocked, and no disturbance caused the loading point, all such operations being done automatically and without the presence of laborers on the track.

120 It is obvious that those skilled in the art may vary the details of construction and arrangements of parts without departing from the spirit of my invention, and therefore I do not wish to be limited to such features except as may be required by the claims.

I claim:

1. In an apparatus of the character described, the combination of a car having movable dumping doors, a device to hold said doors normally closed, means for shifting said device to release the doors, an inclined plane in the path of said doors to return the same to closed position, a platform arranged adjacent said inclined plane, a wear plate for said platform having one end thereof arranged to form a bridge between said inclined plane and platform, resilient means for yieldingly pressing said platform upwardly beneath said doors, and means to restore said door holding means to normal position while the doors are over said platform, substantially as described. 45
2. In a device of the character described, the combination of a car, movable dumping doors for said car, a device for holding said doors in closed position, a trip apparatus in the path of said device to shift the same to permit release of said doors, said trip apparatus including a long lever adapted to be engaged by said device, means for yieldingly holding said lever in the operative position, a short lever adapted to bear in one direction against said long lever, and means for holding said short lever together with said long lever in yielding operative position, substantially as described. 50
3. A device of the character described, including a car, movable dumping doors for said car, a device to hold said doors normally closed, and a trip apparatus including a long lever adapted to be engaged by said device and to shift the device to permit opening of the dumping doors, a short lever, a heavy weight holding said short lever against said long lever, and a light weight holding said long lever in operative position 55
4. In an apparatus of the character described, the combination of a car, dumping doors for said car hinged to swing down in the same direction, latches for keeping both of said doors closed, a lever pivoted between said doors and attached at opposite sides of its fulcrum to said latches, means for throwing said lever to retract all of said latches simultaneously when the car is moved in one direction, and means for restoring said lever and latches to initial position after the doors have been re-closed, substantially as described. 60
5. In an apparatus of the character described, the combination of a car, dumping doors for said car hinged to swing down in the same direction, a latch carried by the car for holding one of the doors in closed position, a latch carried by another of said doors for holding such door in closed position, a lever connected to actuate both of said latches, and means for tripping and restoring said lever to original position, substantially as described. 65
6. In a device of the character described, the combination of a car, dumping doors for said car hinged to swing down in the same direction, a latch carried by said car for engaging one of said doors to hold the same closed, a latch carried by a second door for engaging with the car to hold such door closed, an operating device for the latches, and a hinged connection between said operating device and door-carried latch, substantially as described. 70

In testimony whereof, I affix my signature. 80

DAVID SCOTT ALLISON.
